CUFF LINK

Joseph J. Vastano, 39 Merry Mount Drive,
 Warwick, R.I. 02888
 Filed May 17, 1965, Ser. No. 456,191
 3 Claims. (Cl. 24—97)

This invention relates generally to jewelry devices and in particular to a new and improved form of cuff link.

Heretofore in the jewelry industry the pivotable type of cuff links have been constructed in such a manner that the yoke extending from the ornamental face has a springloaded pivot member extending through holes formed in each yoke and the bar maintained in position by heading over or rivetting. Various disadvantages have been encountered with this type of a cuff link due mainly to the delicateness and fineness of the materials involved. One disadvantage is that the rivet head pulls through the aperture and the device becomes inoperative. Attempts have been made to develop a solid yoke and pivot bar formed by a stamping process which have themselves defeated the end result in not being able to be gold filled. Furthermore, after repeated rotation of the pivotable member the pivot bar has a tendency to wear away the side edges of the pivotable member resulting in a fatigue or failure of the metal.

Therefore, it is an object of this invention to provide an improved cuff link in which the pivot bar is integral with the yoke members.

It is another object of this invention to provide an improved cuff link where the pivotable member is maintained in position and locked between the side members of the yoke.

It is a further object of this invention to provide an improved cuff link which may be formed of drawn stock and in which the pivotable member is spring biased away from the pivot member.

Other objects of this invention will in part be obvious and will in part appear hereinafter.

Broadly stated the feature of this invention is to provide a new and improved cuff link wherein the pivot bar member is formed integral with the side yoke members. By having flange members on the pivot bar member the pivotable shell containing spring members may be maintained in position therein in such a manner that the side walls of the yoke are never under the tendency to be drawn apart.

To the accomplishment of this and the foregoing related ends, the present invention then consists of the means hereinafter fully described and particularly pointed out in the claims, the annexed drawings and the following description setting forth in detail certain means in the carrying out of the invention, such disclosed means illustrating however but one of the various ways in which the principle in the invention may be employed.

FIG. 1 is a view in perspective of the improved cuff link.

FIG. 2 is a view in front elevation partly in section of the improved cuff link.

FIG. 3 is an exploded view of the component parts of the improved cuff link.

FIG. 4 is a view in perspective of the yoke and pivot member of the invention.

Referring to the drawings there is shown in FIG. 1 an improved cuff link 10. The cuff link 10, consists of a yoke member, 12, having side arms 14 and 16, a bottom member 18 and a pivot bar 20. The pivot bar 20, is integral with the side arms 14 and 16 and extends normal thereto and as shown in FIG. 4 substantially parallel to the bottom member 18. As illustrated in FIG. 4, the pivot bar 20 consists of an arm 22, extending at right angles to the side 14 and adjacent the upper end 24 thereof. In a similar manner an arm 26 extends from the side wall 16, adjacent

2

the upper surface 28 and in the direction of the opposite side wall 14. Each of the arms 22 and 26 terminates so that their ends 30 and 32 lie spaced from each other and separated by a gap 34. Flange members 36 and 38 are formed on each of the arms 22 and 26 facing outwardly in the direction of the yoke arms 14 and 16 for a purpose to be set forth more fully hereinafter.

As shown in FIGURES 1 and 3 a pivotable member 40 is adapted to be positioned and rotated around the pivot bar 20 so as to permit the cuff link to be inserted through the shirt cuff (not shown). The pivotable member 40, comprises a shell 42 having downwardly depending side members 44 and 46 with slots 48 and 50 extending upwardly from their free edges 52 and 54 to a point spaced from their upper edges 56 and 58. An inner spring member 60 and an outer spring member 62 which also serves as a closure, sandwich the pivot bar 20 there between and the ends 64 and 66 of the shell 42 are deformed around the outer spring member 62 to retain the pivotable member 40 in assembly with the pivot bar 20.

In operation it will readily be seen by anyone skilled in the art that the shell 42 is positioned with the slots 48 and 50 and has the inner spring 60 extending longitudinally between the ends 64 and 66 over the arms 22 and 26 so that the inner surfaces 68 and 70 of the side members 44 and 46 bear against the flange members 36 and 38 locking the pivot member in position. In this manner, any transverse movement of the pivotable member in the direction of either of the side arms 14 and 16 of the yoke will be compensated. Furthermore, if desired the relative location of the inner spring 60 when utilized in relation to the outer spring 62 in sandwiching the pivot bar 20 therebetween prevents the pivot bar from wearing on the edges of the slots 48 and 50 of the shell ensuring long lived use of the device.

While there have been described herein what are at present considered to be preferred embodiments of the invention, it will be obvious to those skilled in the art that modifications and changes may be made without departing from the essence of the invention. It is therefore to be understood that the exemplary embodiments are illustrative and not restrictive of the invention, the scope of which is defined in the appended claims and that all modifications that come within the meaning and range of equivalency of the claims are intended to be included herein.

What is claimed is:

- An improved cuff link comprising a yoke having an integral bifurcated pivot bar extending transversely across an open end, said pivot bar having a pair of flanges with each of said flanges facing away from each other presenting outwardly and inwardly extending face portions, a spring loaded rotatable shell in co-operative engagement with said pivot bar, said shell having laterally spaced side edges in abutting relation with each of the outwardly extending face portions of said flanges whereby said rotatable shell is freely rotatable on the pivot bar and maintains said arms in fixed spaced relationship.
- An improved cuff link comprising:
  - a yoke having a bottom with
  - sidearms extending substantially normal thereto,
  - a pair of pivot arms extending inwardly from each of said side arms integral therewith with their free ends spaced from each other,
  - outwardly extending flange members disposed on each of said pivot arms at a point spaced from each of said side arms,
  - said flange members having face portions substantially parallel to the side arms,
  - a pivotable member positioned on said pivot arms having spring means in co-operative engagement therewith,

(G) downwardly depending side edges of said pivotable member in sliding engagement with the face portions of said flange members,

(H) the side edges of said pivotable member co-acting with said flange members to lock said pivot arms in fixed spaced relationship.

3. In a cuff link, a yoke having a bottom with sidearms extending substantially normal thereto, a pair of pivot arms extending inwardly from each of said side arms with their free ends spaced from each other, outwardly extending flange members disposed on each of said pivot arms at a point spaced from each of said side arms, said flange members having face portions substantially parallel to the side arms, a pivotable member positioned on said pivot arms having spring means in cooperative engagement therewith, downwardly depending side edges of said pivotable member in sliding engagement with the face portions of said flange members, the side edges of said

5 pivotable member coacting with said flange members to lock said pivot arms in fixed spaced relationship.
